UNITED STATES PATENT OFFICE

CHARLES L. LOW, OF FRESNO, CALIFORNIA, ASSIGNOR TO LISENBY MANUFACTURING COMPANY, OF FRESNO, CALIFORNIA, A CORPORATION

DUPLEX DISK DISTRIBUTOR FOR CYLINDER PRINTING PRESSES

Application filed March 12, 1929. Serial No. 346,327.

This invention relates to printing presses of that type having a reciprocating bed and a revolving cylinder to cooperate with the type set up on the type form of the bed, such as my Patent No. 1,587,968 dated June 8th, 1926; the present invention particularly relating to the ink distributing mechanism of such a press.

In job printing it is frequently desired to do two-color work on the matter printed. With the ordinary presses this must be done by running the matter through the press twice, once for each color. In the type of press above mentioned the desired result is obtained by providing two ink fountains, one at each end of the press. This is an arrangement which of course requires cooperating ductor and form rolls for each fountain and a separate operating mechanism for such rolls of each fountain. This not only adds considerably to the number of parts and complexity of the press but of course increases the cost of manufacture, besides necessitating making the press of considerable length for its actual printing capacity.

The principal object of my present invention is to avoid the above costly and complex structure by providing a two-color inking arrangement for a press of this character having only a single ink fountain and a single ductor roll and set of form rolls to cooperate therewith. The arrangement is such that only one color may be used instead of two if desired, in which case the entire transverse area of the ink plate is available for the one color, or the two colors may be blended. The ink distributing mechanism is such that the bed may move through a relatively short distance while maintaining the ink distributed over the necessary length of the ink receiving plate of the bed; so that in conjunction with the omission of the fountains at both ends the press may be made very compact as to length.

A further object of the invention is to produce a simple and inexpensive device and yet one which will be exceedingly effective for the purpose for which it is designed.

These objects I accomplish by means of

such structure and relative arrangement of parts as will fully appear by a perusal of the following specification and claims.

In the drawings similar characters of reference indicate corresponding parts in the several views:

Fig. 1 is a fragmentary top plan view of a press showing my improved ink distributing mechanism.

Fig. 2 is a longitudinal section on the line 2—2 of Fig. 1.

Fig. 3 is a fragmentary transverse section on the line 3—3 of Fig. 1.

Fig. 4 is a fragmentary side elevation of the vibrator-roll control mechanism.

Referring now more particularly to the characters of reference on the drawings, the numeral 1 denotes the main frame of the press which supports longitudinally extending tracks 2 on which the bed 3 is slidably mounted; a transverse printing cylinder 4 being mounted on the frame intermediate its ends and above the bed. The bed comprises a type form portion 5 at its end nearest the cylinder and a raised ink plate 6 at the opposite end; a pair of transversely spaced ink distributing disks 7 being turnably mounted in said plate and being set flush with the upper surface thereof.

Supported by the frame above the bed and just ahead of the cylinder is a pair of longitudinally spaced form rolls 8, free to rotate and set at such a level that they will alternately engage type mounted on the bed and the ink plate disks.

A vibrator roll 9 is superimposed on and engages both form rolls; said roll being rotated so as to cause the rolls 8 to rotate with the reciprocation of the bed, by gearing 10 secured thereto on one end and meshing with a rack 11 fixed in connection with the bed along its adjacent side. At the end of the frame adjacent the ink plate a transverse ink fountain 12 is mounted, which is preferably of the type shown in my Patent No. 1,681,299 dated April 21st, 1928. This fountain has a fountain roll 13 turnably mounted in connection therewith and is divided into two separate compartments or ink receptacles by a partition 14 engaging the roll. This par-

tition is positioned in longitudinal alinement with the space between the disks and is slightly wider than said space.

The ductor roll 15 is turnably mounted on arms 16 projecting radially from a shaft 17 journaled on the frame, said shaft being arranged to be rotated through a certain arc in timed relation with the reciprocation of the bed, so as to cause the ductor roll to be alternately moved from engagement with the fountain roll to engagement with the adjacent portion of the ink plate and disks when the bed is advanced to its limit of movement adjacent the fountain, as indicated in Fig. 3.

15 The means for intermittently rotating the fountain roll and imparting the necessary movement to the ductor roll supporting shaft may be of any suitable character such as shown in the above mentioned Patent No. 20 1,587,968, and form no part of this invention. The bed is reciprocated through a certain distance, or so as to move the ink plate from a position just ahead of the fountain to a position under the form rolls 8 by suitable 25 means actuated by the rotation of a transverse drive shaft 18 mounted on the frame under the bed.

Such means is shown diagrammatically in Fig. 2 and consists essentially of a crank-arm 30 19 on the shaft, a connecting rod 20 from the crank-arm to a vertical rocker-arm 21 pivoted at its lower end on the frame, and a link 22 from the upper end of the rocker arm to the bed.

35 The vibrator roll 9 in addition to constantly rotating with the reciprocation of the bed may or may not be also moved lengthwise, so as to distribute the ink properly along the surfaces of the rolls 8, by the following means: Secured to one end of the vibrator roll shaft 23 is a grooved collar 24 engaged by one end of an arm 25 which projects radially from a vertical shaft 26 journaled in connection with the frame 1. An arm 40 45 27 projects from the lower end of the shaft at an angle to the arm 25 and is flexibly connected to one end of a longitudinally extending rod 28.

At its other end this rod is flexibly connected to a pin 29 disposed parallel to the shaft 18 and adjustably fixed in a radial slot 30 provided in a disk 31 secured to the adjacent end of the shaft 18. This slot extends to the axial line of the shaft so that 55 the pin may be set concentric with the shaft if desired. By means of this arrangement it will be seen that if the pin is secured in offset relation to the shaft the rod 28 and parts connected thereto will be reciprocated 60 through a certain distance with the rotation of the shaft. If, however, the pin is set at the center of the shaft no movement of the rod will take place and consequently the vibrator roll will not be moved lengthwise. 65 Since the bed advances toward the fountain

only sufficient to cause the ductor roll to engage only small segmental portions of the distributor disks, means is provided for imparting intermittent rotative movement to said disks, between the periods of engagement of the ductor roll therewith, so as to constantly present different segmental portions of the disk for engagement with the ductor roll and thus insure that the entire surface of the disks will be ultimately covered with ink.

70 Such means is constructed as follows: Formed with and depending from the disks are complete circular flanges 32 provided with downwardly projecting ratchet teeth 33. Transversely spaced pawls 34 project upwardly through slots 35 provided in the bottom of the ink plate 6 to constantly engage the ratchet teeth of both disks. The pawls are independently pivoted on the upper 80 ends of arms 36 which are fixed in common on a transverse shaft 37 journaled in a bracket 38 depending from the ink plate. One arm has a substantially horizontal extension 39 projecting therefrom in the direction of the type form portion of the bed and carries a roller 40 on its outer end positioned to engage and ride along an upwardly sloping cam track 41 secured to one of the bed supporting tracks 2.

90 This cam track is so positioned and shaped that the roller will engage the lower end of the same as the bed approaches the fountain, said roller riding up on the track with the advancing movement of the bed so as to cause the arms 36 to be swung forward for a certain distance, and to be then held against movement when the bed completes its travel toward the fountain and the ductor roll moves into engagement with the disks. The 100 disk ratchets and pawls are so arranged that with the forward swinging movement of the pawl supporting arms as above described, said disks will be rotated through a certain 105 arc.

110 As the bed moves in the opposite direction a spring 42 associated with one of the arms 36 retracts said arms with respect to their disk rotating position, such retractive movement being limited by a stop 43 provided in connection with the bracket 38. Since the fountain partition is disposed in a longitudinal plane between the disks as before stated it will be seen that each disk received a supply of ink only from the corresponding receptacle of the fountain and there is no chance for the differently colored inks to get onto the wrong disks; and the ink from the two disks is transferred in segregated 115 relation to the form rolls.

120 When two different colored inks are used the vibrator mechanism of the vibrator roll is positioned so as to be inactive unless it is desired to blend the colors.

If only one color is wanted both fountain 130

sections are filled with the same ink and the vibrator roll is permitted to function.

My improved inking structure may therefore be used for one or two colors as required without any changes or additions being necessary and with only a simple adjustment of the vibrator mechanism pin 29 having to be made for different conditions.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention what I claim as new and useful and desire to secure by Letters Patent is:

1. In a cylinder press, a reciprocable bed, an ink plate provided with the bed at one end thereof, a transverse fountain disposed beyond the plate end of the bed having a fountain roll mounted in connection therewith, a partition in the fountain and engaging the roll to provide two separate ink receptacles, turnable disks mounted in the plate in transversely spaced relation to each other; the partition being disposed in longitudinal alinement with and wider than the space between the disks, and a movable ductor roll for alternate engagement with the fountain roll and disks.

2. In a cylinder press, a reciprocable bed, an ink plate provided with the bed at one end thereof, a transverse fountain disposed beyond the plate end of the bed having a fountain roll mounted in connection therewith, a partition in the fountain and engaging the roll to provide two separate ink receptacles, turnable disks mounted in the plate in transversely spaced relation to each other; the partition being disposed in longitudinal alinement with the space between the disks, a movable ductor roll for alternate engagement with the fountain roll and segmental portions only of the disks, and means for intermittently rotating the disks to cause different portions of the area thereof to be successively engaged by the ductor roll.

3. A structure as in claim 1, with means for intermittently rotating the disks.

4. In a cylinder press, a reciprocable bed, an ink plate provided with the bed at one end thereof, a transverse fountain disposed beyond the plate end of the bed having a fountain roll mounted in connection therewith, a disk turnably mounted on the ink plate, a movable ductor roll for alternate engagement with the fountain roll and a segmental portion of the disk, means for reciprocating the bed, and means functioning with the movement of the bed toward the fountain and

ductor roll for then imparting rotation to the disk, and for causing such rotation to be halted when the bed is on the last portion of its movement toward the fountain whereby to enable the ductor roll to engage the disk while the latter is stationary.

5. In a cylinder press, a reciprocable bed, an ink plate provided with the bed at one end thereof, a transverse fountain disposed beyond the plate end of the bed having a fountain roll mounted in connection therewith, a disk turnably mounted on the ink plate, a movable ductor roll for alternate engagement with the fountain roll and a segmental portion of the disk, means for reciprocating the bed, a circular flange depending from the disk concentric with its axis of rotation, ratchet teeth about the bottom edge of the flange, a pawl engaging the teeth, an arm member on the upper end of which said pawl is pivoted, said member being pivoted intermediate its ends in connection with the ink plate, a roller on the lower end of the arm member, and a horizontal cam-track mounted in a fixed position relative to the bed and engaged by the roller as the bed approaches the fountain end of its stroke and arranged to cause the arm member to be first swung so as to advance the pawl against the teeth and rotate the disk, and to then cause the arm to be held relatively stationary as the bed travels over the last portion of its stroke toward the fountain.

In testimony whereof I affix my signature.

CHARLES L. LOW.
